UNITED STATES PATENT OFFICE.

BENJAMIN NATHAN, OF NEW YORK, N. Y.

DESIGN FOR A BOOT.

SPECIFICATION forming part of Design No. 23,234, dated May 1, 1894.

Application filed December 12, 1893. Serial No. 493,507. Term of patent 14 years.

To all whom it may concern:

Be it known that I, BENJAMIN NATHAN, a citizen of the United States, residing at New York, in the county of New York, State of New York, have invented a certain new and useful Design in a Rubber Overshoe or Boot, of which the following is a specification, reference being had therein to the accompanying drawing.

- 10 The drawing represents a side elevation of a boot having my design.
- 15 The leading features of my design consist in a boot having its leg portion merging into the quarter at a point below and beyond the highest point of the instep with the point of mergence falling within a line drawn perpendicularly from the front edge of the top of the leg, the distance through the leg from front to rear being substantially the same at
- 20 the top and bottom, and the distance through the leg from front to rear being greater than that from the said point of mergence to the toe, this distance being nearly two thirds of the distance from heel to toe at this point.
- 25 The front of the leg portion curves from the top downward and rearward and outward again to the point of mergence of the leg portion and quarter; the ornamental band ex-

tending from the heel to a point beyond the said point of mergence and below the same. 30

In the drawing, A designates the leg portion which merges with the quarter at the point B which is below and beyond the highest point of the instep, the junction being more or less abrupt. The point B falls within the line a—b drawn from the top of the leg as shown, the front of the leg portion curving rearward from the top edge downward and then forward to the point of mergence of the leg portion and quarter, and the leg portion 35 being extended to embrace in its outline the usual instep outline of a boot or shoe. The ornamental band extends from the heel forward of the point of mergence of the leg portion and quarter and below the same, as 40 shown.

What I claim as new is—

The design for a boot substantially as herein shown and described.

In testimony whereof I affix my signature in 50 presence of two witnesses.

BENJAMIN NATHAN.
